UNITED STATES PATENT OFFICE.

HAMMOND B. DOUGLAS, OF WORCESTER, MASSACHUSETTS, ASSIGNOR TO WOODS-SHERWOOD COMPANY, A CORPORATION OF MASSACHUSETTS.

STRAINER.

1,110,483.

Specification of Letters Patent. Patented Sept. 15, 1914.

Application filed May 4, 1912. Serial No. 695,140.

To all whom it may concern:

Be it known that I, HAMMOND B. DOUGLAS, a citizen of the United States, residing at Worcester, in the county of Worcester 5 and State of Massachusetts, have invented a new and useful Strainer, of which the following is a specification.

The principal objects of this invention are to provide a strainer structure which 10 will simplify the mode of manufacture and add to the durability and usefulness of the article.

Reference is to be had to the accompanying drawings in which—

15 Figure 1 is a plan of a strainer constructed in accordance with this invention, and Fig. 2 is a side view thereof.

The invention is shown as applied to a foraminous strainer body 10 of a general 20 hemispherical form, although the form can be varied to suit the conditions, and preferably provided with a cylindrical sheet metal rim 11. The handle 13 is connected with this rim by forming a wire member doubled 25 on itself at its end to form a lip 14; bent upwardly from the end, and then horizontally at the point 15. The two wires of this doubled construction are then separated, each one forming a semi-circle 16 surrounding 30 the body 10 and meeting again exactly opposite the loop. The parts are then twisted together at 17 in order to provide a place for applying the handle and this is shown as having a loop 18 at its end by which the 35 device can be hung on a nail or the like. The circle formed by the two semi-circular members 16 is made of such size as to receive the rim and fit under the bead thereon. After it is put in this place the rim is preferably 40 forced outwardly at three or more points 19 to hold the semi-circular member in position on the rim. In this construction it will be seen that the double projection 14—15 formed at the end of the wire 45 is exactly opposite the handle and forms a flat rest by which the strainer can be supported on a bowl or other dish, the other side being supported by the handle. On account of this being flat the tendency to 50 tip is reduced and on account of its downwardly projecting lip 14 it is not easily dis-

placed endwise. Another advantage is that if on account of the use of the device the strainer becomes injured or worn at one point, it can be turned in this circular member so as to bring the point of greatest wear into another position. But the main advantage is the simplicity of construction and the ease and rapidity with which it can be manufactured mainly by dies. This 60 makes the article very cheap to make and yet it is extremely durable and efficient for the purposes intended.

While I have illustrated and described a simple embodiment of the invention, I am 65 aware that modifications can be made therein by any person skilled in the art without departing from the scope of the invention as expressed in the claim. Therefore I do not wish to be limited to all the details of 70 construction herein shown and described, but

What I do claim is:—

As an article of manufacture, a utensil of the class described consisting of a strainer 75 member embodying a strainer and an annular band attached to the upper edge of the strainer, this band being provided with an outwardly extending flange at its upper edge, and a handle member consisting of a 80 single strand of wire bent upon itself to form a pair of semi-circular members 16 which embrace the band of the strainer member at a point under the flange thereon, said semi-circular members terminating 85 short of each other at one side and both extended outwardly and bent downwardly to form a rest, while at the diametrically opposite point said members are twisted permanently together to form a handle or stem, 90 said band being provided below said semi-circular members with outwardly bent integral means serving to lock said semi-circular members on said band.

In testimony whereof I have hereunto set 95 my hand, in the presence of two subscribing witnesses.

HAMMOND B. DOUGLAS.
